UNITED STATES PATENT OFFICE.

ALEXANDER BLOCK, OF NEW YORK, N. Y.

LOCK.

1,377,456.

Specification of Letters Patent. Patented May 10, 1921.

Application filed January 2, 1920. Serial No. 348,902.

To all whom it may concern:

Be it known that I, ALEXANDER BLOCK, a citizen of the United States, and resident of New York city, in the county of New York 5 and State of New York, have invented certain new and useful Improvements in Locks, of which the following is a specification.

This invention relates to locks, and more particularly to locks that may be used upon 10 both swinging and sliding doors. The principal object of my invention is to provide a bolt that shall securely lock the door when shifted from the casing into a keeper, and subsequently to said locking operation to interlock said keeper with said casing.

The present invention is an improvement upon the invention disclosed in my application filed December 30, 1919. The main object of this improvement is to reduce the 20 number of parts and to simplify the construction of said lock and thus render it less likely to get out of order and cheapen the manufacturing cost thereof.

Other objects and advantages will appear 25 in the specification given herein.

In the accompanying drawing, Figure 1 is a sectional elevation of the lock showing the disposition of the mechanism when in 30 unlocked state. Fig. 2 is a view similar to that shown in Fig. 1, but showing the arrangement of the parts of the lock when in locking and interlocking state. Fig. 1 also shows in broken lines the position of the bolt when in locking state, only prior to being projected into engaging position.

The lock embodied in my invention embraces a metal casing 1 and a keeper 2. A bolt 4 having a hook 5 on its outer or locking end is connected to a frame 3 provided 40 with slots 10 and 11, and projections 8^c and 9^c. A stud 12 on casing 1 is arranged to be received in said slot 10, and a lever or any other suitable device may be provided for projecting the bolt into engaging position, 45 said lever 14 being preferably pivoted on said casing 1 and provided with a stud 13 adapted to be received by slot 11 on said frame 3.

A pawl 19 is pivoted on said frame 3 at 50 22, and comprises a pivot head 21, a projection 20 bearing upon projection 8^c of frame 3, a ledge 23 abutting on a lug 24 on casing 1 and a spring 25 connected at its pivot head 21 and leaning against a stud 26.

Said pawl 19 tends to maintain hooked bolt 55 4 in locking position prior to the projection of said bolt into engaging position.

A pawl-pressed device for actuating said lever 14, said lever actuator 27 being movable in casing 1 and guided in its movement 60 and guarded against displacement laterally by suitable means—not shown. Said actuator is provided with projections 28—29 and a tumbler pawl pivotally mounted thereon at 32. Said pawl embraces a pivot head 31, 65 a projection 34 bearing on projection 28 of actuator 27, a ledge 35 abutting on a lug 36 on casing 1 and a spring 33 attached to its pivot head 31 and leaning against a stud 33^c.

A link 18 is pivotally attached by one end 70 to said actuator 27 and by the other end to lever 14 through an arm 16 attached to said lever 14, which is pivoted on casing 1 at 15.

An arm- or a cam 38 is mounted upon a 75 rotatable sleeve 37, which is rotatable by means of key operated mechanism, and a separate similar device may be operated by means of a knob. Said cams are adapted to operate the locking mechanism, moving the hooked bolt longitudinally and subsequently 80 projecting said bolt into engaging position.

To perform the complete locking operation, cam 38 upon being operated by rotating sleeve 37 by said key mechanism, first 85 releases frame 3 by bearing against projection 20 of pawl 19, then said cam bears against projection 8^c of frame 3 and moves said bolt into locking position in keeper 2, said studs 12 and 13 functioning as guides 90 for said frame 3. In completing the revolution, said cam 38 further encounters said lever actuator 27 and its pawl, bearing against projection 34 of said pawl and releasing said actuator, then bearing against projection 28 of said actuator moves said actuator in a direction to operate lever 14 and cause stud 13 on said lever to swing said bolt 4—5 on stud 12 on the casing as a pivotal point and interlock the casing with the keeper. The pawl 95 on said actuator engages again with lug 36 on casing 1, and thus locks said actuator, said lever and the hooked bolt in operative position, and prevents reverse movement of said hooked bolt from its projected position.

To unlock the door, the above-mentioned 100 mechanisms are moved in the reverse direction.

Having thus described the invention, what

I claim as new and desire to secure by Letters Patent, is:—

1. In a lock, the combination of a lock casing, a hooked bolt adapted for slideable and pivotal movement on said casing, a lever movably mounted on said casing, means for moving said bolt and for subsequently causing said lever to project said hooked bolt into engaging position.
2. In a lock, the combination of a lock casing, a hooked bolt adapted for slideable and pivotal movement on said casing, a lever, means for moving said bolt and for subsequently causing said lever to project the bolt into engaging position, said lever acting to prevent reverse movement of said bolt from said projected position except by the instrumentality of said lever.
3. In a lock, the combination of a lock casing, a hooked bolt adapted for slideable and pivotal movement on said casing, a cam on said casing, means for moving said bolt into locking position, means for preventing reverse movement of said bolt from said position except by the instrumentality of said means, and additional means causing said cam to project the bolt into engaging position, and for locking said bolt in said position.
4. In a lock, the combination of a lock casing, a hooked bolt arranged to move slideably and pivotally thereon, a lever or cam on said casing, means for moving said bolt into locking position, and additional means for subsequently forcing said lever or cam to project the bolt into engaging position, and acting to lock said bolt in said projected position.
5. In a lock, the combination of a lock casing, a hooked bolt, said bolt being adapted for slideable and pivotal movement on the casing, means for moving the bolt longitudinally, a lever or cam, means upon said cam or lever adapted to project the bolt upon actuating said cam or lever, and separate means for operating said lever or cam to cause the bolt to be projected into engaging position subsequently to the locking operation, said separate means acting to prevent reverse movement of said bolt from said projected position.
6. In a lock, the combination of a lock casing, a hooked bolt movably mounted on said casing, a lever or cam upon said casing, an actuator for said lever or cam, means for moving said bolt and for subsequently causing said actuator to force the lever or cam to project the bolt into engaging position, means being provided for locking said bolt in such projected position.
7. In a lock, the combination of a hooked bolt, a lock casing, said bolt being movably mounted on the casing, a bolt projector, means for operating said bolt projector, means for moving said bolt longitudinally and for subsequently causing said means for actuating said bolt projector to cause said projector to move the bolt into engaging position, and to lock said bolt in such position, reverse movement being attainable by the instrumentality of said means.
8. In a lock, the combination of a hooked bolt, a projector, an actuator for said projector, means for moving said bolt into locking position and for subsequently causing said actuator to force the projector to move the bolt into engaging position, separate means being provided for maintaining the bolt in such position.
9. In a lock, the combination of a casing, a hooked bolt mounted for slideable and pivotal movement thereon, a projector, an actuator for said projector, means on said projector adapted to coöperate with means on the bolt for swinging said bolt on its pivotal point, means for moving said bolt into locking position and for subsequently causing said actuator to operate the projector and cause the means on the projector to swing the bolt on its pivotal point into engaging position, and a pawl acting to prevent reverse movement of said bolt from such projected position.
10. In a lock, the combination of a casing, a hooked bolt movably mounted thereon, a projector for said bolt, an actuator for said projector, means for moving said bolt and for subsequently operating said actuator for causing said projector to project the bolt into engaging position, a pawl associated with the bolt for locking the bolt against reverse movement, and a pawl on said actuator acting to prevent reverse movement of the bolt from said projected position, except by the instrumentality of said means.
11. In a lock, the combination of a lock casing, a hooked bolt movably mounted thereon, a projector, an actuator for said projector adapted for slideable movement in said casing, means for guiding the movement of said bolt, means for moving the bolt and for subsequently forcing said actuator to move in a direction to operate said projector and cause the bolt to be projected into engaging position, and means acting to lock said bolt in such projected position, means being provided for guiding the movement of said actuator.
12. In a lock, the combination of a lock casing, a hooked bolt, said bolt being mounted for slideable and pivotal movement on the casing, a projector upon the casing, a projector actuator, key or knob mechanism for moving said bolt and for subsequently moving said actuator in a direction to operate said projector for projecting the bolt into engaging position, a pawl being provided for restricting the bolt longitudinally and a separate pawl being

provided for locking said actuator against reverse movement, said pawl acting to prevent reverse movement of said projector and said bolt from their operative positions, 5 except by the instrumentality of said mechanism.

13. In a lock, the combination of a lock casing, a hooked bolt movably mounted thereon, a projector, an actuator for said projector, means operably connecting said actuator with said projector, and key or knob mechanism for moving said bolt into locking position and for subsequently operating said actuator to cause said projector 10 to move the bolt into engaging position, means being provided for maintaining said bolt in such projected position, reverse movement being attainable by the instrumentality of said mechanism.

14. In a lock, the combination of a hooked bolt, a lock casing, a stud on the casing, means on said bolt for receiving said stud on the casing, a projector, a stud on said projector, means on said bolt for receiving said stud on the projector, an actuator in operative connection with said projector, and key or knob mechanism for moving said bolt along said studs as guides and for subsequently operating said actuator to 20 force the projector to swing said bolt on said stud on the casing as a pivotal point into engaging position, means being provided for preventing reverse movement of the bolt from such position except by the 25 instrumentality of said mechanism.

15. In a lock, the combination of a bolt, one or more hooks on the outer or locking

end thereof, a lock casing, said bolt being adapted for slidable and pivotal movement on said casing, a projecting device, an actuator for said device, said actuator being mounted for slidable movement on said casing, means for guiding the movement of the bolt on the casing, means for guiding the movement of said actuator on the casing, and key or knob mechanism for moving said bolt into locking position and for subsequently operating said actuator and causing said projecting device to move the bolt into engaging position, a pawl being provided for preventing reverse movement of said bolt from said locking position except by the instrumentality of said mechanism, and a pawl associated with said actuator preventing reverse movement of the bolt 50 from said projected position except by the instrumentality of said mechanism.

16. In a lock, the combination of a hooked bolt, a projecting device, an actuator, a link connecting said actuator with said projecting device, means for moving said hooked bolt and for subsequently operating said actuator to cause the projecting device to move the hooked bolt into engaging position. 55

Signed at the city of New York, in the county of New York and State of New York, this 30th day of December, A. D. 1919.
